LIGHTNING STROKE GENERATOR

Peter L. Bellaschi, Sharon, Pa., assignor to Westinghouse Electric & Manufacturing Company, East Pittsburgh, Pa., a corporation of Pennsylvania

Application October 7, 1939, Serial No. 298,445

9 Claims. (CL 171—97)

This invention relates to lightning stroke generators, and particularly to such generators in which are combined a lightning stroke voltage generating apparatus and a lightning stroke current generating apparatus.

Prior to my invention disclosed and claimed in Patent No. 2,032,904, issued March 3, 1936, so-called lightning generators which were utilized for testing the insulation of electrical apparatus were high-voltage impulse generators capable of developing a very high voltage with very little current. In order to provide an electric discharge that more nearly simulates a stroke of lightning, it was necessary to provide for a heavy current discharge starting during the occurrence of the voltage impulse wave and following for a much longer time than the voltage impulse wave. In my patent above referred to, I provide equipment designed to apply current strokes to apparatus under test which would more nearly simulate the destructive forces of heavy lightning currents than did existing apparatus of this character previously employed. Since the time of making the invention covered in my prior patent, however, experimental data has been obtained establishing with greater detail than was at that time known the nature of a lightning stroke discharge, particularly in that the current discharge, in addition to its initial high current wave, may have a relatively long sustained discharge lasting for several times the duration of the high current wave, which is of importance because, due to its time of duration, it may represent a considerably greater dissipation of energy than does the initial high current wave. This sustained current discharge has been shown to be the cause of the fusing of metal parts, or the ignition and burning of combustible material.

Lightning stroke discharges may take several forms. A typical stroke may consist of three characteristic elements—a very high voltage wave of very short time duration, a high current wave of longer duration, and a sustained current flow of moderate value having a much longer time duration. The first, or voltage impulse, may develop to a value of many millions of volts reaching its crest value in about 1 microsecond, the total wave lasting for a duration of time of the order of 2 to 4 microseconds. The second element, or initial current surge, may rise to a crest value of from several thousand amperes to 200,000 amperes from 5 to 10 microseconds, reducing to one-half the crest value in from 50 to 200 microseconds, 100 microseconds being typical. The third characteristic element of the

stroke, or sustained discharge, may be of the order of 100 to 5000 amperes, continuing from 1000 microseconds to 10,000 to 100,000 microseconds. Any one of the two current elements of the discharge may at times occur alone, or they may both occur in the same discharge in various amounts or degrees.

Observations and experiments have shown that the characteristic effect of the first, or high-voltage discharge, is to puncture insulating material of high dielectric value; the characteristic effect of the second element or high current impulse, is the shattering or splintering of objects affected thereby; and the characteristic effect of the third, or sustained current discharge, is that of burning, melting or igniting the objects to which it is applied. It has been shown, for example, that a high current wave of 100 microseconds duration, which will splinter strong dielectric material and hurl the parts with great violence in all directions, cannot be made to ignite even readily inflammable material, such as cloth or excelsior, or to damage electrical conducting metals, while the third, or sustained discharge of from 100 to 5000 amperes for a duration of 1000 microseconds or longer, will both burn or ignite combustible materials, and will melt or fuse large voids in solid electrical conducting metal objects. This third characteristic element of the typical lightning stroke is somewhat similar, in effect, to short-circuit power currents of great current values lasting for from one-half cycle to several cycles duration, or to a direct-current flow of equal energy dissipation. Not all lightning strokes have all three characteristic elements. They may have the first, or impulse voltage element, with either the high current wave of short duration or the sustained current wave of longer duration, or both, or there may be a current wave of irregular characteristic following a voltage discharge, which wave may have several high current peaks of short duration with comparatively low current values between them.

Another characteristic of the lightning stroke discharge is the repetition of several strokes in close succession. Such strokes usually each start with an impulse voltage wave and may be followed by current discharges of the character pointed out above.

It is an object of my invention to provide a lightning stroke current generator of a type that will produce a relatively long sustained current discharge that is characteristic of the burning or heating portion of a typical lightning stroke.

It is a further object of the invention to provide a lightning stroke generator of the type above indicated for delivering a high-voltage surge discharge, a relatively high current surge discharge of relatively short duration, and a relatively low current discharge of relatively long duration.

It is a further object of my invention to provide a lightning stroke generator for developing a plurality or series of lightning stroke discharges in quick succession.

Referring to the drawings:

Figure 1 is a diagrammatic view of apparatus and circuits for producing a lightning current discharge of long duration;

Fig. 2 is a diagrammatic view of apparatus for combining the initial high-voltage and high current discharge with the sustained moderate current discharge of long duration;

Fig. 3 is a diagrammatic view of another embodiment of apparatus for producing a lightning current discharge of long duration combined with the lightning discharge of shorter duration;

Fig. 4 is a diagrammatic view of circuits and apparatus for effecting a series of lightning strokes in quick succession;

Fig. 5 is a view of the tripping switch for controlling the sequential discharge of the lightning stroke generators illustrated in Fig. 4; and

Fig. 6 is a diagrammatic view of another embodiment of apparatus for developing a multiple stroke discharge.

Referring to Fig. 1 of the drawings, a voltage impulse generator 1 is illustrated in combination with apparatus including a transformer 2 for developing a sustained current discharge of moderate value for several thousand microseconds. The transformer 2 is provided with a high-voltage winding 1 and a low-voltage winding 8, and is connected by a circuit controlling device 9 to a source of alternating current represented by the circuit conductors 12. The device 9 may be a mechanical switch, or it may be other suitable apparatus, such as an igniton timer, well known in the art for permitting current flow for a selected duration of a half-cycle or more. The winding 7 is connected between terminal conductors 4 and 5 of the test-piece 3 under test, the circuit including a de-ion gap 13 and a spark gap 14. The de-ion gap 13 consists of a fusible wire 15 within a tube 16 of insulating material, such as fibre, or other equivalent material.

The high-voltage impulse generator 1 consists of a plurality of capacitors 17 connected to discharge in series through a plurality of sphere gaps 18, establishing a high voltage between ground at 21 and the sphere gaps 19, which voltage is applied across the test-piece 3 to ground at 6 and across a high ohmic resistor 22 connected in parallel therewith. The condensers 17 are connected to be charged in parallel from conductors 23 and 24 through individually associated resistors 25 and 26 from a source of energy, represented generally at 27, and including an alternating-current transformer 28 having a high-voltage winding supplying two rectifiers 31 and 32 connected in circuit with electrical storage devices, such as capacitors 33 and 34, to the midpoint of which the high-voltage transformer winding is connected through a resistor 35, and to the outside terminals of which the rectifiers 31 and 32 are connected.

A gap device, including spheres 36, 37 and 38, is provided for initiating the discharge of the voltage impulse generator 1, the two elements

36 and 37 being connected respectively to adjacent capacitors 17. The intermediate sphere 38 is connected to a tripping and synchronizing circuit for determining the exact moment of discharge with respect to the alternating current supplied to the conductors 12, so that the discharge occurs at the desired part of the alternating-current wave.

A simplified tripping and synchronizing circuit for this purpose is illustrated as comprising a push button 40 for closing a circuit to energize a step-up transformer 41, one output terminal of which is connected to the middle electrode 42 of a triple gap device 43, the two outer terminals 44 and 45 of which are connected to the other terminal of the other output terminal of the step-up transformer 41 through a resistor 46 and a capacitor 47, respectively, so that the triple gap device 43 breaks down at or near the crest of the voltage wave of the transformer 41. The terminal electrode 44 is connected by conductor 48 to the intermediate sphere 38 of the main triple gap device 39, the connections being such that the intermediate gap electrode 38 is thus given a potential which is opposite to the potential of the ungrounded electrode 37 of the main gap device, so that the gap between the spheres 37 and 38 first breaks down, after which the full voltage of the lower condenser 17 is applied to the gap between the spheres 36 and 38, causing it to break down. The flow of current through the gap device 39 so modifies the potentials across the succeeding gaps 18 of the impulse generator as to cause the entire series of gaps to break down and apply the entire series voltage of the several capacitors 17 to the gap 19, which in turn breaks down applying the high-voltage impulse to the test-piece 3.

The discharge of the high-voltage impulse generator 1 causes the gap 14 to break down and connect the transformer 2 to the test-piece 3 through the de-ion gap 13. The timing of the discharge of the voltage impulse generator may be such as to occur during the early portion of a half-cycle output from the transformer 2. It will be noted that a half-cycle at 60-cycle frequency has a duration of 8333 microseconds. Thus the number of half-cycles is controlled to attain the desired duration. The interruption of the sustained current wave from the transformer 2 may be effected either by the setting of the fused de-ion gap 13 or by the operation of the circuit breaker 19 on the low-voltage side of the transformer. Tests have been made with the equipment disclosed in Fig. 1, with varying amount of current and duration of wave thus showing that the same amount and nature of fusion of metal objects can be produced as those observed from natural lightning, the equipment simulating the long sustained current discharges of lightning causing such heating or burning of the materials.

Fig. 2 discloses a lightning stroke generator combining the voltage impulse generator 1 and the long sustained current generator 2 with a current impulse generator 51 corresponding to that disclosed in my Patent No. 2,032,904, and comprising a plurality of capacitors 52 connected in parallel between terminal buses 53 and 54 that are connected across the test-piece 3 through an impedance device 55 upon the breakdown of gap 56, which occurs upon the discharge of the voltage impulse generator 1. The device 55 comprises a high resistance fusible link 57 within an insulating tube 58 of fibre or other equivalent material. The device 55, which appears in the diagram

to be similar to the device 13 and resembles it structurally, performs a different function from the device 13, and for that purpose the fusible link is of high resistance of the order of one to several hundred ohms, so as to prevent enough of the impulse voltage discharge from entering the current generator 51 to produce a voltage sufficient to break down the insulation of the test-piece 3. The fuse link 57, after 1 or 2 microseconds, converts into a low resistance arc, so that the discharge of the current generator follows immediately after the high-voltage discharge through or across the test-piece 3. Also, the fiber tube 58 serves to interrupt the current 15 after the high current discharge and segregate the current generator 51 from the test object 3.

The lightning stroke generator diagrammatically illustrated in Fig. 2 will supply an initial high-voltage surge from the generator 1, causing the spark gaps between the spheres 56 and 14 to break down to supply respectively an initial high current impulse surge from the generator 51 and a sustained current surge of lesser current value, but of longer time duration from 25 the current generator 2, to simulate the three element characteristic of a lightning stroke described above.

Fig. 3 illustrates a lightning stroke generator for developing the same three-element characteristic discharge including the voltage impulse generator 1, the impulse generator 51, and an impulse generator 61, which may be similar in general nature to the generator 51 and consisting of a plurality of capacitors 62, 63, 64 and 65 connected to bus terminals 66 and 67 for applying a current surge across the test-piece 3 upon the breakdown of the gap between spheres 68, which occurs upon the discharge of the voltage impulse generator in the manner above described. The 40 impulse generator 61 discharges through an impedance or resistor device 69 that is of a value sufficient to limit the discharge current to the moderate value typified by the sustained discharge of a lightning stroke as described above. The capacity of the generator 61 must be sufficient to supply the desired discharge current for the time necessary to simulate such sustained discharge. It will be appreciated that in the several surge generators 1, 51 and 61 the number 50 of capacitors actually used will be much greater than those shown to diagrammatically illustrate such generators. It will also be appreciated that where it is desired to apply the discharge from any of the several current generators 2, 51 or 61, 55 the tripping circuit shown in Fig. 1, employing a middle terminal 38, may be applied to any of the gaps between spheres 14, 56 or 68. Thus any one of the three characteristic elements of the lightning surge pointed out above may be applied separately to the test-piece, if desired.

Fig. 4 illustrates a lightning stroke generator capable of supplying repeated impulses in rapid succession. It consists of a plurality of lightning stroke generators 11, 12, 13 and 14, which are here illustrated as each corresponding in nature to the voltage impulse generator 1 shown in Figs. 1, 2 and 3. For the purpose of simplicity, only the voltage impulse generators are shown, although it will be appreciated that there may 70 be associated with each of the voltage impulse generators any of the combinations of current impulse generators shown in Figs. 1, 2 and 3, or any of the current impulse generators may be used alone to provide a series of repeated current impulses without the use of the voltage im-

pulse generators, if desired. The sequential operation of the several voltage generators is controlled by a rotating disc 15 operated by a motor 16, as shown in Fig. 5, and carrying thereon a sphere 17 which, as it rotates, comes 5 between a pair of spheres 18 and 19 to partially bridge the gap therebetween and cause the discharge of initiating condensers 81, 82, 83 and 84 to thus secure the proper interval of time between the discharge of the successive lightning 10 stroke generators. Thus each of the generators may be designed to have suitable voltage and current characteristics at a discharge in proper sequence to simulate the multiple stroke discharge of certain types of lightning strokes. 15

Fig. 6 shows other apparatus for producing a multiple stroke discharge. A large power transformer 91 is provided, receiving energy from supply conductors 92 and 93 as controlled by a switch 94. The transformer supplies charging 20 current to a large high-voltage capacitor 95 during a half-cycle or several half-cycles output of the same polarity from transformer 91, which is effected by the proper operation of the switch 94. As the switch 94 receives a full voltage 25 charge, the gap between spheres 96 breaks down, discharging to ground at 97, and applying the discharge voltage across the test-piece 3. By suitable control of the switch 94, the number and sequence of condenser discharges is adjusted 30 as desired. A de-ion gap device 98 may be provided in the circuit for interrupting the circuit through the gap between spheres 96. In Fig. 6, a transformer 99 is shown for applying power voltage excitation to the test-piece 3, so that the impulse test may be made with full power excitation applied thereto in accordance with the method of testing described in United States Patent 1,957,306, issued to F. J. Vogel on May 1, 1934, and assigned to the same assignee as this 40 application. It will also be appreciated that the apparatus disclosed in Figs. 1 to 4 may be used with the application of dynamic power across the insulating material during the discharge of the lightning stroke generator through or across 45 the material or test-piece 3 being tested.

It will be apparent to those skilled in the art that many modifications of the apparatus and circuits illustrated may be made within the spirit of my invention, and I do not wish to be limited 50 otherwise than by the scope of the appended claims.

I claim as my invention:

1. A combined lightning-stroke current and voltage generator comprising an impulse voltage generator including a plurality of capacitors connected to discharge in series, an impulse current generator having a low-impedance, high-current discharge characteristic for delivering a large current for a short duration of time including 55 a plurality of capacitors and buses for connecting said capacitors in parallel, an impulse current generator having a high-impedance, low-current discharge for delivering a relatively lower current for a relatively longer time comprising a 60 plurality of capacitors, buses connecting said capacitors in parallel, and an impedance device in circuit with said buses for limiting the rate of discharge thereof, terminal connections for a 65 test-piece, means for controlling the connection 70 of said terminal connections to said impulse voltage generator, and means responsive to the discharge of said impulse voltage for connecting said impulse current generators to said terminal connections. 75

2. A combined lightning current and voltage generator comprising an impulse voltage generator including a plurality of capacitors connected to discharge in series, an impulse current generator having a low-impedance high-current discharge characteristic for delivering a large current for a relatively short duration of time comprising a plurality of capacitors and buses connecting said capacitors in parallel, means for 5 delivering a current discharge of relatively lower current value for a relatively longer time, terminal connections for a test piece, means for controlling the connection of said terminal connections to said impulse voltage generator, and means responsive to the discharge of said impulse voltage generator for effecting the discharge of 10 said two current discharge devices.
3. A combined lightning-stroke current and voltage generator comprising an impulse voltage generator including a plurality of capacitors connected to discharge in series, capable of delivering a discharge voltage wave rising to several 15 million volts in 1 microsecond, an impulse current generator characterized by sufficient capacity to give a maximum crest value of discharge 20 of the order of 100,000 amperes and capable of sustaining the current flow above one half its crest value for 100 microseconds, an impulse current generator having sufficient capacity to deliver 25 a discharge current of the order of 5,000 amperes for a duration of several thousand microseconds, terminal connections for a test piece, means for controlling the connection of said terminal connections to said impulse voltage generator, and means responsive to the discharge of 30 said impulse voltage for connecting said impulse current generators to said terminal connections.
4. A combined lightning current and voltage generator comprising an impulse voltage generator including a plurality of capacitors connected to discharge in series, an impulse current generator having a low-impedance high-current discharge characteristic having sufficient capacity 35 for delivering a current wave having a crest value of the order of 100,000 amperes and capable of sustaining the current flow above one half its crest value for a time of the order of from 2000 to 7000 microseconds, means for delivering 40 a current of the order of 5000 amperes for a duration from three thousand to five thousand microseconds, terminal connections for a test piece, means for controlling the connection of said terminal connections to said impulse voltage generator, and means responsive to the discharge of 45 said impulse voltage for connecting said impulse current generators to said terminal connections.
5. A combined lightning-stroke current and voltage generator comprising an impulse voltage generator including a plurality of capacitors connected to be discharged in series, an impulse current generator having a high-impedance low-current discharge for delivering a discharge current 50 for a duration of several thousand microseconds comprising a plurality of capacitors, buses connecting said capacitors in parallel, and an impedance device in circuit with said buses for limiting the discharge thereof, terminal connections for a test piece, gap means for controlling the connection of said terminal connections to said impulse voltage generator, and means responsive to the discharge of said impulse voltage generator for connecting said current generator to said terminal connections.
6. A combined lightning-stroke current and voltage generator comprising an impulse voltage generator including a plurality of capacitors connected to be discharged in series, means for delivering a current discharge of the order of 2000 amperes to 5000 amperes for a duration of the order of from 2000 microseconds to 7000 microseconds, terminal connections for a test piece, gap means for controlling the connection of said terminal connections to said impulse voltage generator, and means responsive to the discharge of 15 said impulse voltage generator for connecting said current generator to said terminal connections.
7. A combined lightning-stroke current and voltage generator comprising an impulse voltage generator including a plurality of serially connected capacitors, an impulse current generator including a plurality of capacitors connected in parallel and an impedance device for limiting the current flow therefrom to the order of 5000 amperes, the capacitors having sufficient capacity 20 to deliver a discharge current of that order for a duration of several thousand microseconds, terminal connections for a test piece, means for controlling the connection of said terminal connections to said impulse voltage generator, and means responsive to the discharge of 25 said impulse voltage generator for connecting said impulse current generator to said terminal connections.
8. A lightning-stroke generator comprising a plurality of impulse voltage generators each comprising a plurality of capacitors connected to discharge in series, terminal connections for a test piece, means for controlling the connection of said terminal connections to said several impulse voltage generators in predetermined sequence and at predetermined spaced time intervals.
9. Apparatus comprising a plurality of lightning-stroke generators each including an impulse voltage generator having a plurality of capacitors connected to discharge in series, an impulse current generator having a low-impedance high-current discharge characteristic for delivering a current of the order of 100,000 amperes for a duration of from 40 to 200 microseconds, and means for delivering a current discharge of the order of 5000 amperes for a duration of several thousand microseconds, terminal connections for a test piece, means including spark gaps for controlling the connection of said terminal connections to several lightning-stroke generators in a predetermined sequence at predetermined short time intervals.

PETER L. BELLASCHI.
